John Whiting & John Munn of Boston Massachusetts
Sellers. Patent

Their schedule referred to in their Letters Patent and making part of the
same containing a description in the words of the said John Whiting and
John Munn, themselves of their improvement in the construction of stoves for cooking

To all to whom these presents shall come. John Whiting of the City of
Boston in the County of Suffolk and Commonwealth of Massachusetts &
John Munn of Brookline in the County of Norfolk in the said Commonwealth
Gentlemen and Brethren. Be it known that we the said Whiting and
Munn have jointly invented made and applied to use a new and useful
improvement in the construction of stoves for cooking to be heated
by the burning of either wood or coal or peat, which invention and in-
provement we describe and specify as follows, that is to say Figure
numbered one, in the drawings, hereto annexed as a part of this Spe-
cification, and description represents a stove constructed upon our
invented plan, when put together, and figures numbered two, three
four, five and six, represent several parts thereof, letter A represents
the end door next to the furnace, between this door and the grate
where the fire is kindled is a partition of cast iron about three
fourths of an inch in thickness, part whereof is seen in figure num-
bered one and is represented by the letter S. This partition is so
heated by the fire that when the door A, which is also of cast
iron is thrown open meat of any kind may be roasted and
cooked by being brought and kept for a sufficient time near to the
said partition. The object of the door A is to prevent the heat from be-
ing thrown off when it is unnecessary. Letter B represents the pit into
which the ashes falls from the grate and into which by opening the door
R, which slides horizontally inward, the air may be admitted so as
to pass up through the bottom of the grate and ventilate the fire.
C represents a sliding register to the oven door which is represented
by D, and is of cast iron, the object of the register is to facilitate the ex-
(cept)

of moisture in the operation of roasting, and to prevent its escape in baking. E represents a similar cast iron register on the cast iron furnace door, which is represented by F. The object of this register is to admit the air for the purpose of ventilating the fire. Both the sliding door and the register in the furnace door may be conveniently used together or separately as may be required, so as to admit the air horizontally or perpendicularly or in both ways to the fire which must be regulated according to the nature of the fuel, and to the circumstances as must be obvious. G. represents the end of the stove opposite to that where the furnace is, and at this end is an aperture represented by H. leading to the flue on the side of and under the oven, which is opened and closed by the sliding door H. The object of this aperture is to facilitate the cleaning of the flues from soot and ashes when required, and the door is to close the aperture when required so as to prevent the escape of the hot, or entrance of the cold air, from or to the flues. I. is ~~the~~ ^a box attached to the stove into which the hot air and smoke pass from the flues, and upon which box is the projection K made for receiving the funnel to carry off the hot air and smoke. L represents the interior of the oven for baking and roasting. L represents the flues which pass around the oven, and through which the hot air and smoke pass in the direction of the arrows from the top of the furnace, over the top of the oven, then down by the side of the oven and then under the bottom thereof and up to the other side so as to come in contact with a cast iron partition by which it is separated from the furnace and thence into the projection L, through an aperture in the back of the stove and thence off the funnel. M. represents a space under the grate M, which is of cast iron and slides readily in and out upon ledges or projections on the cast iron partition, which form sides of the furnace. There are two ledges on each side so that the grate may be fixed higher or lower at pleasure as the nature of the fuel and the case may require. N represents a slide in the back of the stove to open and close ^{the} aperture near the top for the purpose of increasing the draft of air through the fire when re-

caution may require, it leads from the top of the furnace immediately into the projection at A, independently another slide which opens and closes an aperture from the flues into the same projection to regulate the passing off of the hot air and smoke. It is the sliding door before mentioned seen in figure numbered one, for admitting air and removing ashes when required. B is the before mentioned partition beneath the door at, seen in the same figure. C, D, represent apertures, one over the oven, and the other over the furnace for receiving boilers for cooking and through that over the furnace the fuel may be put into the grate, and that over the oven facilitates the clearing of the flues from soot and ashes. Covers adapted to these apertures are to be placed over them when the boilers are not there. We have made our stoves of cast iron entirely excepting rods, hinges and such like things, and cast iron is deemed best, but wrought iron may be used. A flat plate of cast iron standing on legs with a sunk hearth or pit from three to four inches deep, and four to expand three quarters inches in width extending nearly across, and covered in part by said sliding door B, from the bottom or foundation of the stove. There are ledges on the sides of the oven to support shelves when required; By the passing of the heated air first over the top then down by the side, and then under the bottom of the oven, a more even and regular heat is communicated to all parts of the oven than by other means now in use, and by allowing it to pass between the oven and furnace, it becomes more rarefied, and causes a greater draught of the air.

And we hereby declare that what we claim as new and of our invention is the construction of such stoves as aforesaid, and the several parts thereof not separately, but in combination for the purposes aforesaid, and also the construction of stoves so that the hot air may pass first over them down by the side of and then under the oven and then between the oven and the furnace in manner aforesaid and for the purposes aforesaid. The construction of the oven and furnace may be somewhat varied at discretion, and the side door for roasting may be dispensed with if thought advisable, but the construction above mentioned is deemed most

9093X

convenient in all cases. We do not however intend to confine our last claim above mentioned to any particular form or construction of the oven or furnace, excepting only such form as may be necessary to convey the heat out from the furnace around the oven in the way and manner aforesaid for the purposes aforesaid, and we have described the form which we deem most convenient but it may be somewhat varied at discretion as is obvious. In testimony that the above is a true specification of our invention we have hereunto set our hands this eighth day of August in the year of our Lord Eighteen hundred and thirty five.
